OIL BURNING APPARATUS

Forrest A. Heath, Upper Montclair, N. J.

Application February 10, 1928, Serial No. 253,270
Renewed December 5, 1930

23 Claims. (Cl. 158—4)

My present invention concerns oil burning apparatus of the class in which metered, and more or less mixed oil and air are sprayed, preferably centrifugally above a refractory hearth that 5 closes in the lower end of a fire box and more specifically to apparatus having the oil projecting means and the hearth organized and operating in such combination that in normal full operation as well as at starting, the flame line or region 10 where active combustion is precipitated is localized adjacent the periphery of the hearth which thus functions as the "burner." My present invention more particularly concerns the use in such a combination of a hearth peculiarly 15 adapted to improve the certainty and speed of ignition; to lessen the danger of having the ignited oil flame put out by being smothered in excess gas evolved at starting; and, in normal full 20 operation, to more certainly localize at the periphery, the zone where active combustion is precipitated.

To these ends, one feature of my invention involves having the periphery of the hearth terminate in a vertical impingement wall of fire 25 brick or the like, adapted to afford a catalytic surface to precipitate combustion at the periphery after it gets highly heated in normal running. This impingement wall extends upward to the highest horizontal level to which the oil can be 30 projected by the projecting apparatus, so that most of the projected oil impinges thereon. Another feature is a collecting gutter or groove at the base of this wall, of cross section sufficient to hold all of the unignited oil that can collect 35 during the starting period. Preferably, this peripheral gutter is a pronounced groove, deep enough so that the exposed top surface of the oil collected therein is of small area.

Another feature cooperating well with the collecting gutter, but which may be sufficient in 40 itself, is to provide for an out drainage of the hearth downward from the oil projector to the periphery. Preferably, the upper surface is sloped so that it will be close to but substantially out of 45 range of the trajectory of the lowest part of the projected oil. Where such down slope hearth is used, it necessarily forms a collecting annulus or gutter at the base of the above described impact wall, so that in certain cases any more 50 pronounced groove may be dispensed with.

From the above, it will be evident that while in many cases, particularly in fire boxes of small diameter, the groove may be useful with a hearth having a horizontal upper surface or even with 55 one having a slight up-slope outwardly and while

the down slope outwardly is capable of use without the groove, the down slope plus the pronounced groove mutually cooperate to produce the best results. In such combination, the outward down slope tends to keep the hearth free 60 from impingement of unignited oil and facilitates outward drainage of any that does impinge, while the groove tends to minimize the exposed surface of the oil collected therein.

Another novel feature of special utility in connection with a hearth that has an upper surface which does not drain by gravity toward the center, is setting the air and oil projector close to the center of the hearth so that the projected air sweeps the surface of the hearth while the oil projector remains high enough so that in normal full operation the projected oil cannot impinge on the hearth. When the air is thus discharged over a hearth in which the upper surface is unobstructed and approximately parallel 70 with the air draft, the under surface of the air draft tends to follow the upper surface of the hearth, thereby minimizing tendency of the air to eddy back and flow reversely toward the center of the hearth, as is commonly the case, where the fan delivers the air at a level very substantially above that of the hearth, as in all prior apparatus where the path of the projected oil lies above the hearth and combustion is 75 precipitated by impact of the air and oil upon a 80 peripheral ignition wall.

As a result, I am able to start the oil projector by projecting only the amount of oil necessary for normal running, yet I accumulate at the periphery where it is to be ignited, an ample supply 85 of oil, in even less time than would be possible by an over-supply of oil projected upon the usual up-slope or horizontal hearth which does not have any peripheral gutter. Thus the oil is concentrated at the desired ignition point so that it 90 is readily ignited. Moreover, after it is ignited, the excess oil volatilizes gradually from the surface downward. There is no large area of oil on the adjacent hearth, where it would be volatilized by the flame in quantities sufficient to smother 95 the growing flame and put out the pilot light or ignition torch.

Another feature of my invention is a small, continuously flowing pilot jet projecting upward in the collecting groove, in combination with an 100 ignition torch adapted, when turned on, to discharge in igniting relation to the constantly burning pilot.

The above and other features of my invention 105 will be more evident from the following descrip- 110

tion in connection with the accompanying drawing, in which

Fig. 1 is a plan view of the hearth and burner, the surrounding fire box and water leg being as shown in horizontal section;

Fig. 1a is an enlarged sectional detail showing more clearly and fully the fan and draft arrangements of the burner head; and

Fig. 2 is a vertical section on the broken line 10 2-2, Fig. 1.

The furnace to be heated is shown in Fig. 2 as including a support annulus 1, closing in a space which may be approximately the same as the ash pit space of an ordinary coal fire furnace. This 15 supports the furnace which may be of any desired construction, the essential parts shown in Fig. 2 being the wall 2 closing in the fire box and an outer wall 3 affording an interspace 4 for the water or air to be heated or boiled, as the case 20 may be. An annular ledge 5 supports a plate or metal hearth pan 6, which in turn supports a refractory hearth 7 through which projects a burner, more or less diagrammatically indicated at A.

The hearth is formed at its periphery with the 25 vertical ignition wall 8 having at the base thereof an oil collecting gutter, in this case a semi-cylindrical groove 9, into which project the pilot flame nozzles 10, 10. The ignition torches 11, 11 are in such position that when the gas is turned on, 30 the jets are each ignited by a continuously discharging pilot 10.

Various examples of oil and air projectors suitable for my purpose are now well known. One is the oil projector invented by Homer A. Tiffany, 35 for which application for Letters Patent has been made, Ser. No. 355,688 filed April 17, 1929, and another is set forth in my application Ser. No. 47,709, filed August 3rd, 1925, which has resulted in Patent No. 1,707,474, issued April 2, 1929.

40 The oil is centrifugally discharged in an extremely fine spray or vapor through nozzles 12, supplied through a head 13 mounted on vertical shaft 14 which is an extension of an armature shaft of an electric motor contained in the casing 45 A. This motor is of the usual construction and rotates the head at the usual high speed to project the oil from the nozzles 12, 12, in a trajectory, the upper and lower regions of which are indicated in a general way by the dotted lines 50 X and Y, respectively. The head carries fan blades 15 creating a powerful draft below the trajectory of the oil as suggested by the arrow Z. As shown in Figures 2 and 1a, there are ten or a dozen fan blades 15 carried by the under face of 55 the head 13. These constitute a large volume fan tending to create a vacuum in the interior space a. The four nozzles 12 constitute another fan creating suction at e, and through annular passage d this suction takes effect in the same space 60 that the fan 15 draws from. The air inlet to this space a is through a slot b communicating with the ash pit. The cross section of this slot may be adjustably decreased or increased by vertical slide c. Thus, the many blades 15 and the four 65 nozzles 12 constitute two fans drawing in parallel from the same source. The respective suction effects of these two fans are very nearly the same, but the amount of air delivered through 12 is much smaller than delivered through 15, because 70 the flow section of the four little nozzles is very much less than that of the annulus through which blades 15 discharge.

In operation, oil is supplied to the trough e through a suitable interior nozzle not shown. Centrifugal force causes a film of this oil from

trough e to creep up the walls and ultimately to be thrown off as a fine spray projected from the rear lips of the four nozzles 12. Centrifugal force also causes a relatively small volume of air to be projected through these nozzles 12 while a much larger volume of air is being projected by the fan blades 15. The nozzles project substantially above the plane of the top plate 13 of the rotor. Consequently, said plate, together with the upwardly projecting surfaces of the nozzles constitutes in effect a third fan whereby hot products of combustion are projected in the same horizontal plane with spray. The projected products of combustion and the air enveloping the spray lose velocity more quickly than the spray, so that the spray tends to cut through the paths of the former. Thus the composite draft produced by the nozzles consists of a mixture of hot products of combustion, spray and a small percentage of air. When this composite mixture strikes the periphery of the hearth, the spray is further atomized and mixed with the primary air and gas and also with the air from the fan blades. These easily ignite, at starting, and when the apparatus is in full operation so that the refractory impact surfaces are at high heat, the combustion at the periphery is substantially perfect.

As shown in Figure 2, the rotary head is set very close to the hearth so that air discharged therefrom sweeps the surface of the hearth from the center outward, as indicated by the arrows Z, thus maintaining a smoothly flowing draft of air between the hearth surface and the projected oil. This is a great improvement over the arrangement shown in my prior Patent 1,707,474, 100 and now commonly practiced in the art. In such cases, the peripheral ignition wall is much higher than the center of the hearth so that when the head is set high enough to throw oil against said wall, the fan is so high that the air from the 105 under surface of the draft discharged thereby eddies backward toward the head instead of sweeping the surface of the hearth outward from the center to circumference. The oil and air supplies to the burner, as also the means for 110 metering the same, form no part of my present invention and are not shown. Similarly, the means for continuously supplying gas to the 115 pilot nozzles 10 and intermittently supplying gas to the ignition torches 11 may be of any known 120 or usual construction and are not shown. The 125 important features are that the pilot nozzles 10 project above the highest level at which oil can collect in the groove 9, when the ordinary control apparatus required by the fire underwriters, 130 is employed; also the ignition torch nozzles 11 are located inside the circumference of the collecting groove and the flame therefrom impinges obliquely upon the ignition wall, tending to drive the flame obliquely into the groove and around the wall, preferably in the same direction of rotation that the rotary head tends to rotate the body of air or gas within the fire box.

If desired, supplemental air may be admitted 135 through the hearth by nozzles 17, 17, which also discharge toward the ignition wall obliquely in the same direction as the ignition torches.

I have discovered by many experiments that an outward down slope for the hearth of approximately $\frac{1}{2}$ inch to the foot is sufficient to keep the upper surface below the trajectory of the oil, even when the diameter of the fire box is a maximum. As a specific illustration of preferred construction, I may note that an 8-inch rotary head 12, 13, may be utilized for fire boxes of 140 145 150

widely varying diameter simply by varying the metering of the oil and gas, a uniform running speed of, say, 1700 revolutions per minute being maintained for all sizes of furnace and all degrees of heat. Where such a head is used in a fire box having a hearth only 24 inches in diameter, the oil only has to be thrown 8 inches. In such a case, a slight down slope to the hearth is desirable, although the distance is so short that all of the oil may be discharged with certainty against the ignition wall, regardless of whether the upper surface of the hearth is horizontal or is slightly sloping in either direction. For such small diameters, a collecting groove alone is amply sufficient for my purpose without the slope. With greater diameters, the outward down slope is progressively of greater importance, but for all sizes of hearth up to, say, 78 inches in diameter, the standard outward down slope of $\frac{1}{2}$ inch to the foot is sufficient. The collecting depression may be a relatively shallow gutter, but I prefer a semi-cylindrical groove an inch or more in diameter.

The operation of the above apparatus may be described as follows:

The pilot jets, 10, are small and are continuously supplied with gas sufficient to ignite the jet from ignition torch 11, whenever the gas is turned on. The usual controls are employed whereby power is supplied to rotate the head 13 to deliver a predetermined metered supply of oil along the lines X, Y and air or air and hot gas, as indicated by the arrow Z, and also to turn on the gas through ignition torch 11. The ignition torch is immediately lighted by the pilot light and the oil projected against ignition wall 8 collects in groove 9. The maximum exposed surface of oil is therefore practically limited to the area of said ignition wall and the upper surface area of the oil in groove 9. All of the oil being concentrated in the ignition region, the ignition torches quickly ignite the oil around the entire periphery, but, as before noted, such ignition does not bring into play any increased oil surface, because by my present invention there is little if any smearing or collecting of oil on the upper surfaces of the hearth. Consequently, the igniting operation is quick and uniformly progressive until the entire periphery flames and the controls usually employed for such purposes turn off the ignition torch 11 whenever ignition is fully established.

It will be noted that the pilot light may be and frequently does cease to be flaming when the oil is being rapidly vaporized and burned in close proximity thereto. This is no disadvantage because the amount of gas escaping is small and is burned along with the oil vapor so long as normal operation continues. The important point is that when the oil projector is turned off and the oil flame dies down, it naturally dies down to the ignition wall and into the groove, thus relighting the pilot light before itself becoming extinguished.

While I have shown the fire box as being circular, it is to be understood that in practice they are often rectangular. In such cases the peripheral impingement wall preferably follows the fire box wall in the relation indicated in cross section in Fig. 2, although it is often desirable to have it cut across the extreme angles of the corners. The object in all cases is that the zone in which the active combustion is precipitated may be close enough so that the rising flame will hug the surface of the water leg.

I claim:

1. Apparatus of the class described, including a fire box, a refractory hearth closing in the bottom thereof, and a rotary power driven head comprising a centrifugal oil sprayer and a fan operating to maintain an outwardly flowing draft of air between the oil spray and the hearth, said hearth having a substantially unobstructed upper surface lying below the level of discharge of the oil spray, all designed and operating to initiate combustion adjacent the periphery of the hearth; said hearth having adjacent its periphery an upwardly extending, refractory impact wall of a height sufficient to intercept substantially all of the oil projected by the projecting means and having its upper surface sloping downwardly toward its periphery, and terminating in an oil-tight, oil-collecting gutter adjacent the base of said ignition wall. 80

2. Apparatus of the class described, including a fire box, a refractory hearth closing in the bottom thereof, and a rotary power driven head comprising a centrifugal oil sprayer and a fan operating to maintain an outwardly flowing draft of air between the oil spray and the hearth, 95 said hearth having a substantially unobstructed upper surface lying below the level of discharge of the oil spray, all designed and operating to initiate combustion adjacent the periphery of the hearth; said hearth having its upper surface 100 in the form of a frustum of a flat cone draining outwardly toward the periphery and having a peripheral oil collecting gutter adjacent the base of said ignition wall. 105

3. Apparatus of the class described, including 110 a fire box, a refractory hearth closing in the bottom thereof, and a rotary power driven head comprising a centrifugal oil sprayer and a fan operating to maintain an outwardly flowing draft of air between the oil spray and the hearth, 115 said hearth having a substantially unobstructed upper surface lying below the level of the discharge of the oil spray, all designed and operating to initiate combustion adjacent the periphery of the hearth; said hearth having adjacent its periphery an upwardly extending, refractory ignition wall of a height sufficient to intercept substantially all of the oil projected by the projecting means and having a peripheral oil collecting gutter; in combination with a continuously 120 burning pilot light maintained by a nozzle projecting upwardly adjacent said wall and an ignition torch located nearer the center and adapted to discharge in a direction to be ignited by said pilot light when the gas is turned 125 on. 130

4. Apparatus of the class described, including a fire box, a refractory hearth closing in the bottom thereof, and a rotary power driven head comprising a centrifugal oil sprayer and a fan 135 operating to maintain an outwardly flowing draft of air between the oil spray and the hearth, said hearth having a substantially unobstructed upper surface lying below the level of discharge of the oil spray, all designed and operating to 140 initiate combustion adjacent the periphery of the hearth; said hearth having adjacent its periphery an upwardly extending, refractory ignition wall of a height sufficient to intercept substantially all of the oil projected by the projecting means and having a peripheral oil collecting gutter; in combination with a continuously burning pilot light maintained by a nozzle projecting upwardly through the bottom of said gutter and an ignition torch located nearer the 145 150

- center and adapted to discharge in a direction to be ignited by said pilot light when the gas is turned on.
5. Apparatus of the class described, including a fire box, a refractory hearth closing in the bottom thereof, and a rotary power driven head comprising a centrifugal oil sprayer and a fan operating to maintain an outwardly flowing draft of air between the oil spray and the hearth, said 10 hearth having a substantially unobstructed upper surface lying below the level of discharge of the oil spray, all designed and operating to initiate combustion adjacent the periphery of the hearth; said hearth having adjacent its periphery an upwardly extending, refractory ignition wall of a height sufficient to intercept substantially all of the oil projected by the projecting means and having its upper surface sloping downwardly toward its periphery; in combination with a continuously burning pilot light 15 maintained by a nozzle projecting upwardly adjacent said wall and an ignition torch located nearer the center and adapted to discharge in a direction to be ignited by said pilot light when the gas is turned on.
6. Apparatus of the class described, including a fire box, a refractory hearth closing in the bottom thereof, and a rotary power driven head comprising a centrifugal oil sprayer and a fan 20 operating to maintain an outwardly flowing draft of air between the oil spray and the hearth, said hearth having a substantially unobstructed upper surface lying below the level of discharge of the oil spray, all designed and operating to initiate combustion adjacent the periphery of the hearth; said hearth having its upper surface sloping downwardly toward its periphery and having a peripheral oil collecting gutter; in combination with a continuously burning pilot light 25 maintained by a nozzle projecting upwardly through the bottom of said gutter and an ignition torch located nearer the center and adapted to discharge in a direction to be ignited by said pilot light when the gas is turned on.
7. Apparatus of the class described, including a fire box, a refractory hearth closing in the bottom thereof, and a rotary power driven head comprising a centrifugal oil sprayer and a fan operating to maintain an outwardly flowing draft 30 of air between the oil spray and the hearth, said hearth having a substantially unobstructed upper surface lying below the level of discharge of the oil spray, all designed and operating to initiate combustion adjacent the periphery of the hearth; said hearth having adjacent its periphery an upwardly extending, refractory impact wall of a height sufficient to intercept substantially all of the oil projected by the projecting means and having its upper surface sloping downwardly toward its periphery and having a peripheral oil 35 collecting gutter adjacent the base of said ignition wall.
8. Apparatus of the class described, including a fire box, a refractory hearth closing in the bottom thereof, and a rotary power driven head comprising a centrifugal oil sprayer and a fan operating to maintain an outwardly flowing draft of air between the oil spray and the hearth, said 40 hearth having a substantially unobstructed upper surface lying below the level of discharge of the oil spray, all designed and operating to initiate combustion adjacent the periphery of the hearth; said hearth having adjacent its periphery an upwardly extending, refractory ignition wall of a height sufficient to intercept substantially all of the oil projected by the projecting means and having its upper surface sloping downwardly toward its periphery and having a peripheral oil 45 collecting gutter adjacent the base of said ignition wall.
9. Apparatus of the class described, including a fire box, a refractory hearth closing in the bottom thereof, and a centrifugal oil and air projector discharging horizontally above the hearth, said projector and hearth being of the type designed and operating to initiate combustion adjacent the periphery of the hearth; said hearth having adjacent its periphery an upwardly extending, refractory ignition wall of a height sufficient to intercept substantially all of the oil projected by the projecting means and having a peripheral oil collecting gutter; in combination with a continuously burning pilot light 50 maintained by a nozzle projecting upwardly adjacent said wall and an ignition torch located nearer the center and adapted to discharge in a direction to be ignited by said pilot light when the gas is turned on and to discharge obliquely along said wall.
10. Apparatus of the class described, including a fire box, a refractory hearth closing in the bottom thereof, and a centrifugal oil and air projector discharging horizontally above the hearth, said projector and hearth being of the type designed and operating to initiate combustion adjacent the periphery of the hearth; said hearth having adjacent its periphery an upwardly extending, refractory ignition wall of a height sufficient to intercept substantially all of the oil projected by the projecting means and having a peripheral oil collecting gutter; in combination with a continuously burning pilot light 55 maintained by a nozzle projecting upwardly adjacent said wall and an ignition torch located nearer the center and adapted to discharge in a direction to be ignited by said pilot light when the gas is turned on and to discharge obliquely along said wall.
11. Apparatus of the class described, including a fire box, a refractory hearth closing in the bottom thereof, and a centrifugal oil and air projector discharging horizontally above the hearth, said projector and hearth being of the type designed and operating to initiate combustion adjacent the periphery of the hearth; said hearth having adjacent its periphery an upwardly extending, refractory ignition wall of a height sufficient to intercept substantially all of the oil projected by the projecting means and having a peripheral oil collecting gutter; in combination with a continuously burning pilot light 60 maintained by a nozzle projecting upwardly adjacent said wall and an ignition torch located nearer the center and adapted to discharge in a direction to be ignited by said pilot light when the gas is turned on and to discharge obliquely along said wall and into said gutter.
12. Apparatus of the class described, including a fire box, a refractory hearth closing in the bottom thereof, and a centrifugal oil and air projector discharging horizontally above the hearth, said projector and hearth being of the type designed and operating to initiate combustion adjacent the periphery of the hearth; said hearth having adjacent its periphery an upwardly extending, refractory ignition wall of a height sufficient to intercept substantially all of the oil projected by the projecting means and having a peripheral oil collecting gutter; in combination with a continuously burning pilot light 65 maintained by a nozzle projecting upwardly adjacent said wall and an ignition torch located nearer the center and adapted to discharge in a direction to be ignited by said pilot light when the gas is turned on and to discharge obliquely along said gutter in the direction of rotation of said projector.
13. Apparatus of the class described, including a fire box, a refractory hearth closing in the bottom thereof, and a centrifugal oil and air projector discharging horizontally above the hearth, said projector and hearth being of the type designed and operating to initiate combustion adjacent the periphery of the hearth; said 70

- hearth having adjacent its periphery an upwardly extending, refractory ignition wall of a height sufficient to intercept substantially all of the oil projected by the projecting means and having its upper surface sloping downwardly toward the periphery; in combination with a continuously burning pilot light maintained by a nozzle projecting upwardly adjacent said wall and an ignition torch located nearer the center and adapted to discharge in a direction to be ignited by said pilot light when the gas is turned on and to discharge obliquely along said gutter in the direction of rotation of said projector. 5
13. Apparatus of the class described, including a fire box, a refractory hearth closing in the bottom thereof, and a centrifugal oil and air projector discharging horizontally above the hearth, said projector and hearth being of the type designed and operating to initiate combustion adjacent the periphery of the hearth; said hearth having its upper surface sloping downwardly toward its periphery and having a peripheral oil collecting gutter; in combination with a continuously burning pilot light maintained by a nozzle projecting upwardly through the bottom of said gutter and an ignition torch located nearer the center and adapted to discharge in a direction to be ignited by said pilot light when the gas is turned on and to discharge obliquely along said gutter. 10
14. Apparatus of the class described, including a fire box, a refractory hearth closing in the bottom thereof, and a centrifugal oil and air projector discharging horizontally above the hearth, said projector and hearth being of the type designed and operating to initiate combustion adjacent the periphery of the hearth; said hearth having its upper surface sloping downwardly toward its periphery and having a peripheral oil collecting gutter; in combination with a continuously burning pilot light maintained by a nozzle projecting upwardly and an ignition torch located nearer the center and adapted to discharge in a direction to be ignited by said pilot light when the gas is turned on and to discharge obliquely along said gutter. 15
15. Apparatus of the class described, including a fire box, a refractory hearth closing in the bottom thereof, and a centrifugal oil and air projector discharging horizontally above the hearth, said projector and hearth being of the type designed and operating to initiate combustion adjacent the periphery of the hearth; in combination with a continuously burning pilot light maintained by a nozzle projecting upwardly, and an ignition torch located nearer the center and adapted to discharge in a direction to be ignited by said pilot light when the gas is turned on and to discharge obliquely along said periphery. 20
16. Apparatus of the class described, including a fire box, a refractory hearth closing in the bottom thereof, and a centrifugal oil and air projector discharging horizontally above the hearth, said projector and hearth being of the type designed and operating to initiate combustion adjacent the periphery of the hearth; in combination with a continuously burning pilot light maintained by a nozzle projecting upwardly and an ignition torch located nearer the center and adapted to discharge in a direction to be ignited by said pilot light when the gas is turned on and to discharge obliquely along said periphery, together with an air inlet conduit through 25
- along said periphery in the same direction as said torch, said direction being the same as the direction of rotation of said projector. 30
17. Apparatus of the class described, including a fire box, a refractory hearth closing in the bottom thereof, and a rotary head embodying a centrifugal oil sprayer and a fan operating to maintain an outwardly flowing draft of air between the oil spray and the hearth, said hearth having a substantially unobstructed upper surface lying below the level of discharge of the oil spray, all designed and operating to initiate combustion adjacent the periphery of the hearth; said hearth having adjacent its periphery an upwardly extending, refractory, ignition wall of a height sufficient to intercept substantially all of the oil projected by the projecting means; and a peripheral oil collecting gutter adjacent the base of said ignition wall and lying below the level of said unobstructed upper surface of the hearth. 35
18. Apparatus of the class described, including a furnace, a hearth closing in the bottom thereof, a power driven centrifugal projector discharging air and oil horizontally, adjacent the upper surface of the hearth, said hearth having a burner portion adjacent its periphery, all designed and operating to initiate combustion in a peripheral zone at the location of said burner portion, the latter being formed with elements having upwardly extending, inwardly presented surfaces adapted to intercept the path of the projected oil and air and deflect them upwardly while vaporizing and producing a homogenizing effect on said oil and air; said parts being formed and arranged to afford an oil-tight oil collecting depression below the inwardly presented surface of the burner portion and below the level of the upper surface of the hearth, into which excess unvaporized oil flows by gravity from said upwardly extending inwardly presented surfaces of the burner portion. 40
19. Apparatus of the class described, including a fire box, a refractory hearth closing in the bottom thereof, a power driven rotary head provided with centrifugal oil spraying means and with a centrifugal air projecting fan, both discharging above the level of the hearth, said hearth having refractory ignition surfaces projecting upwardly adjacent its periphery, designed and located so as to intercept practically all of the projected oil spray; the fan and hearth being designed and arranged so that the under surface of the draft as it leaves the fan sweeps the central portion of the hearth; and the upper surface of said hearth from the central portion outward toward the ignition surfaces being substantially uniform and unobstructed and sloping downward toward its periphery so as to afford a guide for and to be swept by the under surface of said air draft, thereby minimizing tendency to downward eddying and reverse flow of air from said under surface of the air draft toward the projector; and means for regulating the amount of air supplied to the fan; all designed and operating to initiate combustion adjacent the periphery of the hearth. 45
20. Apparatus of the class described, including a fire box, a refractory hearth closing in the bottom thereof, a power driven rotary head provided with centrifugal oil spraying means and with a centrifugal air projecting fan, both discharging above the level of the hearth, said hearth having refractory impact surfaces adjacent its periphery, designed and located so as 50

to intercept practically all of the projected oil spray and having an oil collecting gutter adjacent the base thereof; the fan and hearth being designed and arranged so that the under surface of the draft as it leaves the fan tends to sweep the upper surface of the central portion of the hearth; and said upper surface of the hearth from the central portion outward toward the impact surfaces being sloped so that surplus oil drains outward from the center and so as to afford a uniform unobstructed guide surface swept by the under surface of said draft, until the air reaches a peripheral zone where mixing with the oil is to be effected and combustion precipitated.

21. Apparatus of the class described, including a furnace affording a combustion chamber, a hearth closing in the bottom of said chamber, said hearth being provided with a central opening and an upwardly extending peripheral wall; a power driven centrifugal projector projecting through said opening and arranged to afford a central annular inlet for an air draft, said projector having a head discharging oil and projecting the air draft approximately horizontally adjacent the upper surface of the hearth, said upper surface of the hearth having a slight outward and downward slope so as to be approximately parallel with the air draft projected by the head, and so as to drain oil toward the periphery of the hearth; all designed and operating to initiate combustion in an annular zone adjacent said peripheral wall.

22. Apparatus of the class described, including a furnace affording a combustion chamber, a hearth closing in the bottom of said chamber and

provided with a central opening, a power driven centrifugal projector projecting through said opening and arranged to afford a central annular inlet for an air draft, said projector having a head discharging oil and projecting the air draft approximately horizontally adjacent the upper surface of the hearth; said upper surface of the hearth having a slight slope outward and downward from the head so as to be approximately parallel with the air draft projected by the head, and so as to drain oil toward the periphery of the hearth, in combination with an annular refractory element adjacent the furnace wall formed with inwardly presented impact surfaces disposed in the path of said oil and air to deflect the same while vaporizing the oil and producing a homogenizing effect on said oil and air; and all designed and operating to initiate combustion in an annular zone adjacent said annular refractory element.

23. Apparatus of the class described, including a firebox, a refractory hearth closing in the bottom thereof and a power driven rotary head comprising a centrifugal oil sprayer and a fan operating to maintain an outwardly flowing draft of air and oil spray, said hearth having a substantially unobstructed upper surface close to but below the level of discharge of the oil spray, and having adjacent its periphery an upwardly extending refractory impact wall in the path of oil and air projected by the projecting means, said upper surface of the hearth sloping downwardly toward its periphery and terminating in an oil-tight, oil-collecting annulus adjacent the base of said wall.
